(57) **CLAIM**

The ornamental design for a deck board fastener, as shown and described.

DESCRIPTION

FIG. 1 is a top perspective view of a deck board fastener without the clip engaged;

FIG. 2 is a top perspective view of a deck board fastener with the clip engaged;

FIG. 3 is a bottom perspective view of a deck board fastener of FIG. 2;

FIG. 4 is a top plan view of a deck board fastener with the clip engaged of FIG. 2;

FIG. 5 is a bottom plan view of a deck board fastener of FIG. 2;

FIG. 6 is a left side view of a deck board fastener of FIG. 2;

FIG. 7 is a right side view of a deck board fastener of FIG.

2;

FIG. 8 is a front view of a deck board fastener of FIG. 2; and,

FIG. 9 is a back view of a deck board fastener of FIG. 2.

The broken lines in the drawings illustrate portions of the

deck board fastener and form no part of the claimed design.

1 Claim, 7 Drawing Sheets
